UNITED STATES PATENT OFFICE.

CHARLES HAMM, OF PITTSBURG, PENNSYLVANIA, ASSIGNOR TO GEORGE A. MACBETH, OF SAME PLACE.

DESIGN FOR A LAMP-CHIMNEY.

SPECIFICATION forming part of Design No. 19,836, dated May 13, 1890.

Application filed February 18, 1890. Serial No. 340,961. Term of patent 14 years.

To all whom it may concern:

Be it known that I, CHARLES HAMM, of Pittsburgh, in the county of Allegheny and State of Pennsylvania, have invented a new and useful Design for Lamp-Chimney Tops; and I do hereby declare the following to be a full, clear, and exact description thereof.

My design consists in a lamp-chimney top having a flared mouth and a depending flange extending down from and surrounding the same and ornamentation on said flange.

In the drawings, Figure 1 is a side view of a chimney illustrating my design. Fig. 2 is a vertical central section thereof; and Fig. 3 is 15 a cross-section on the line 3 3, Fig. 2.

The chimney *a* has the mouth *b*, which is flared, and has the annular depending flange *c* surrounding that mouth. This flange is ornamented on the lower portion thereof or on 20 the base thereof, as shown at *c'*, the ornamentation formed on the depending flange

illustrated in the drawings being a series of globular beads, this globular beading giving a fine finish to the flange, so greatly improving the appearance of the chimney. Any desired ornamentation may, however, be formed upon the side or base of the depending flange of the chimney.

What I claim as my design, and desire to secure by Letters Patent, is—

The design for a lamp-chimney herein shown and described, consisting in the top having a flaring mouth, a depending flange extending down from and surrounding the same, and ornamentation on the said flange.

In testimony whereof I, the said CHARLES HAMM, have hereunto set my hand.

CHARLES HAMM.
